DRIER

Harlow L. Schmidt, Milwaukee, Wis., assignor to
The Hell Co., a corporation of Wisconsin

Application March 27, 1937, Serial No. 133,365

4 Claims.

(Cl. 34—5)

My present invention relates in general to improvements in the art of heating, and relates more specifically to improvements in the construction and operation of internally heated drums having peripheral annular supporting elements or tires coating with rotary members such as rollers to rotatably support the drums.

Generally defined, an object of the present invention is to provide an improved mounting for rotary cylinders or the like, and improved instrumentalities for preventing excessive heating of the supporting elements.

It has heretofore been common commercial practice to support the drums of rotary driers, kilns and the like upon tires secured to the outer shells and coating with rollers journaled in stationary supporting structure. Due to the intense internal heat, the supporting tires are frequently subjected to sufficiently high temperatures to warp and otherwise distort the same, thereby not only producing irregular rotation of the drums but also subjecting the tires to excessive stress and possible rupture. It is however desirable for structural reasons, to attach the tires directly to the shell of the drum near the end heads, and in extremely long shells intermediate tires may also be required. In most devices of this general class, it is also undesirable to provide deep pockets near the end heads, within which material tends to accumulate, but dishing of the heads in order to eliminate such pockets is rather costly and objectionable for this reason.

My present invention therefore contemplates the provision of improved means for preventing excessive heating of the supporting tires of a drier drum or the like, due to internal heat.

My invention also contemplates the provision of improved means for eliminating undesirably deep pockets near the end heads of a drum, within which material tends to lodge.

The invention furthermore contemplates the provision of simple and effective structure for insulating or segregating the supporting tires of a drier drum from the internal heated zones by ventilated air spaces, while at the same time obviating deep material collecting corners and pockets within the shell of the drum.

These and other specific objects and advantages of the present invention will be apparent from the following detailed description.

A clear conception of embodiments of the features constituting my present improvement, and of the mode of constructing and of operating driers built in accordance with this invention, may be had by referring to the drawing accompanying and forming a part of this specification

wherein like reference characters designate the same or similar parts in the several views.

Fig. 1 is a substantially longitudinal vertical section through a rotary drier embodying the improvement;

Fig. 2 is a part sectional end view of the drier of Fig. 1, looking toward the feed end thereof;

Fig. 3 is a considerably enlarged section taken through the feed end corner of the drier drum of Fig. 1; and

Fig. 4 is a similarly enlarged section through the feed end corner of a slightly modified assemblage.

While my invention has been shown and described herein as being specifically applied to a particular type of drier drum and for the specific purpose of protecting a smooth annular peripheral tire from detrimental effects of internal heat, it is not the intent to thereby unnecessarily restrict the scope, since the improvement is also applicable to other types of rotary drum drives and for the protection of such drives against any kind of temperature changes.

Referring to the drawing, the improved drier shown rather diagrammatically in Figs. 1 and 2, comprises in general a drum assemblage consisting of three concentric elongated shells 6, 7, 8 and end closure heads 9, 10, 11 coating therewith; a hot gas supply duct or pipe 12 and a material supply spout 13 communicating with the feed end of the inner shell 6; an outlet pipe 14 communicating with the discharge end of the outer shell 8 and with an exhaust fan 15; peripheral tires 16 secured to the opposite ends of the outer shell 8 adjacent to the end heads 9, 10; and rotary supporting rollers 17 coating with the tires 16 and being journaled in the bearings 18 carried by suitable foundation beams 19. The gas supply pipe 12 is fixed and communicates with any suitable source of hot gas, and the material supply spout 13 is also stationary and may be provided with a rotor as shown for regulating the delivery of fibrous or granular material into the inner drum shell 6 with the heated gases. The outlet pipe 14 is also stationary, and the exhaust fan 15 is adapted to constantly create a flow of mixed gas and fibrous material through the revolving drum assemblage and to deliver the treated mixture to a suitable separator. The interiors of the shells 6, 7, 8 may also be provided with internal flights for showering the solid particles across the interiors of these shells so as to enhance the drying action, but these flights form no part of the present invention and have therefore been omitted in order to avoid confusion.

55

The shells 6, 7, 8 and the end heads 9, 10, 11 may be formed of sheet metal and are preferably welded together to produce a strong but relatively light drum assemblage. The inner shell 6 has its inlet end provided with a sealing plate 20 which coacts with the fixed supply pipe 12, and the shell 6 extends longitudinally within the intermediate shell 7 and is supported concentric therewith by means of a ring 21 and radial gussets 22 disposed near the end head 11 which encloses an end of the shell 7. The opposite end of the intermediate shell 7 is supported concentrically of the outer shell 8 by means of a similar ring 23 and gussets 24, near the end head 9; and the space between the end heads 10, 11 has a series of radial flights 25 therein which cooperate with a cone 26 on the exterior of the end head 11 to deliver the treated material into the outlet pipe 14. The outer end head 10 may also be provided with a sealing plate 20 coacting with the pipe 14, and a deflecting cone 27 may also be provided on the inner face of the end head 11, but these details of construction are relatively unimportant so far as my present invention is concerned. It is to be noted, however, that the relative mounting of the concentric shells 6, 7, 8 and the location of the end heads 9, 10, 11, is such that a continuous circuitous path is provided in the drum assemblage, extending from the inlet pipe 12 to the outlet pipe 14, and the gussets 22, 24 as well as the flights 25 are radially disposed.

The tires 16 are rigidly attached, as by welding, to the periphery of the outer shell 8, adjacent to the end heads 9, 10, and the gusset 24 and flights 25 extend into the annular corners formed by the end heads and the shell 8 directly within these tires. The shell 8 is also embraced by a jacket 28 of insulating material, which extends from one tire 16 to the other, and the end heads 9, 10 may also be covered with like insulation, if so desired. In accordance with the present invention, in order to segregate the tires 16 from the heated interior of the drum, a series of segment plates 29 are inserted across the corners of the outer shell 8 between the successive radial gussets 24 and flights 25, to provide substantially annular air spaces 30 having substantially triangular cross-section, as clearly shown in Fig. 3. In order to vent these annular spaces 30, the end heads 9, 10 are provided with openings 31 whereby the heated air may escape and cool air may enter the spaces 30. Besides providing insulating air spaces 30, these segment plates 29 also eliminate the deep pockets exposed to the drum interior, and within which solid particles might otherwise tend to accumulate, and these pockets are obviously done away with without necessity of dishing the end heads 9, 10.

The segment plates 29 may be either straight or curved as shown, and the spaces 30 may be additionally vented as in Fig. 4, by shortening the insulating jacket 28 and by providing other openings 32 in the shell 8 laterally adjacent to the tires 16. The radial gussets 24 and flights 25 extending into the spaces 30, will then act as fan blades tending to draw fresh air into the side openings 31 and to deliver the air through the peripheral openings 32.

During normal operation of the improved drier, heated gas from any suitable source is being constantly delivered into the inlet end of the central shell 6 through the pipe 12, together with the material which is to be treated, this material being constantly discharged in regulated quantity

from the supply spout 13 into the entering stream of hot gas. The drier drum is being constantly rotated from any suitable source of power, through the supporting rollers 17 which frictionally engage the tires 16. The suction fan 15 is operating to constantly draw the mixture of material and gases through the shells 6, 7, 8 in succession as indicated by the arrows in Fig. 1, and the flights 25 normally function to deliver the finally treated material into the discharge pipe 14 from whence it is withdrawn by the fan 15 and is delivered to the separator. In this manner, the material admitted from the feed spout 13 is constantly dried and is delivered in dried condition to a separator or other point of utilization.

Because of the relatively high temperature of the gases passing through the drum, the shell 8 and end heads 9, 10 will naturally become heated. In order to prevent the tires 16 from becoming excessively heated, I have provided the segment plates 29 which form the chambers or spaces 30 segregating the tires 16, from the heated interior of the drum. While the air within the spaces 30 may tend to heat, the openings 31 will quickly disperse this heat and will thereby prevent excessive heating of the tires 16. The plates 29, besides providing substantially annular insulating air spaces for the tires 16, also eliminate deep pockets between the successive radial vanes or plates at the corners formed by the junctions of the end heads 9 with the shell 8, thereby preventing the material being treated from accumulating at these corners. The provision of the openings 31 does not materially weaken the end heads 9, 10, and if additional ventilation of the spaces 30 is required, openings 32 such as shown in Fig. 4, may also be provided.

From the foregoing detailed description, it will be apparent that the present invention provides simple and highly efficient means for protecting the tires 16 against excessive heating due to the high internal temperatures prevailing within the drum. The tire insulating means also functions to prevent accumulation of material in the corners of the drum structure, and all of these advantageous results are obtained by merely placing the segment plates 29 diagonally across the corners and by providing ventilating openings 31. The assemblage can obviously be produced at extremely moderate cost and functions automatically to produce the desired results.

It should be understood that it is not desired to limit this invention to the exact details of construction or to the precise mode of operation herein shown and described, for various modifications within the scope of the claims may occur to persons skilled in the art.

I claim:

1. In combination, an internally heated drum having outer and inner shells, an annular series of radial plates for supporting said inner shell from said outer shell, a tire secured to the periphery of said outer shell adjacent to said plates, and a series of segment plates connecting the successive supporting plates and providing an air space between said tire and the heated drum interior.

2. In combination, a drum having an outer shell provided with end heads and an inner shell disposed within said outer shell between said heads, radial plates connecting the ends of said inner shell with the adjacent end heads and with said outer shell, a tire secured to each end of said outer shell near the adjacent end head, and a series of segment plates connecting the

successive radial plates near each end head to provide air spaces between said tires and the interior of said drum.

3. In combination, a rotary drum having an annular end corner separated into segments by a series of plates, an annular driving element secured to said drum at said corner, and an annular series of segment plates connecting said first mentioned plates to provide an annular air chamber at said corner separating said element from the drum interior.

4. In combination, a cylindrical drum having at each end an annular corner divided into segments by a series of radial plates, an annular tire secured to the periphery of said drum at each of the cornered ends thereof, and annular series of segment plates connecting the radial plates of each set to provide annular triangular sectioned air chambers at said corners separating said tires from the drum interior.
